UNITED STATES PATENT OFFICE

131,307

DESIGN FOR A VALVE REFACING AND RESEATING TOOL

Ole O. Rothe and Israel Diebel, Minneapolis,
Minn.

Application October 31, 1940, Serial No. 96,230

Term of patent 14 years

To all whom it may concern:

Be it known that we, Ole O. Rothe and Israel Diebel, citizens of the United States, residing at Minneapolis, in the county of Hennepin and State of Minnesota, have invented a new, original, and ornamental Design for Valve Refacing and Reseating Tools, of which the following is a specification, reference being had to the accompanying drawing, forming part thereof, and in which

Figure 1 is a side view of a refacing and reseating tool, showing my new design;

Figure 2 is a top view of the tool; and

Figure 3 is a bottom view thereof.

We claim:

The ornamental design for a valve refacing and reseating tool, substantially as shown.

OLE O. ROTHE.
ISRAEL DIEBEL.
